TRANSMITTER

Manfred W. Muehler, Nutley, N. J., assignor to
American District Telegraph Company, Jersey
City, N. J., a corporation of New Jersey

Original application January 12, 1938, Serial No.
184,595. Divided and this application April 22,
1942, Serial No. 439,985

15 Claims. (Cl. 177—378)

This invention relates to transmitters for alarm systems, and more particularly to transmitters of the code wheel type adapted to transmit current impulse signals of predetermined character. The invention further relates to a modification or improvement of the transmitting apparatus disclosed in applicant's prior Patent No. 2,109,273, granted February 22, 1938, the present application being a division of applicant's prior Patent No. 2,309,660, granted February 2, 1943, application Ser. No. 184,595, filed January 12, 1938.

The object of the invention is to improve the construction and operation of a code transmitter of the character described.

Another object of the invention is to provide transmitting means of the code wheel type which will be effective to generate different signals at different times or under different conditions.

Another object of the invention is to provide a unitary transmitting means which will transmit one signal or series of current impulses when the associated apparatus such as a water flow detector is rendered operative, and transmit a different signal or series of current impulses from the same code generating elements in case the associated device or water flow detector is tampered with.

Another object of the invention is to provide, in connection with a system for supervising the operation of a valve or other device, improved means for indicating or signaling the fact that the supervisory apparatus has been deranged or tampered with, preferably at a remote supervisory station.

Another object of the invention is to provide improved means for transmitting supervisory or alarm and restoration signals when the device supervised operates (or is operated) and when it is restored to normal, respectively.

A still further object of the invention is to provide an improved arrangement for delaying the operation of signaling means where, as in the case of water flow supervisory apparatus, the operation is likely to be improperly initiated by a momentary impulse such as a water surge in the pipe line.

Other objects and advantages of the invention will appear from the following description of the preferred embodiment thereof shown in the accompanying drawing, wherein:

Fig. 1 is a diagrammatic view of a transmitter and supervisory system embodying the invention, the controlling and recording apparatus being only shown in sufficient detail to render the operation of the transmitter clear; and

Figs. 2 to 4, inclusive, are graphs representing the signals sent by the transmitter under assumed conditions.

Referring to Fig. 1 of the drawing, a water-flow transmitter is illustrated which is arranged for the transmission of repeated alarm signals to a printer or other receiver at the central office upon the operation of a water-flow switch in a sprinkler system. The transmitter shown is one of several at different points along the loop circuit from the central office, said circuit comprising the starting, running and common conductors 11, as indicated. The system features, including the operation of several transmitters on a common loop circuit, the supervision of the circuit wires and the central station control- and recording equipment, are covered in the above-mentioned Patent No. 2,309,660, of which the present application is a division, and also in my copending application Serial No. 350,622, filed August 3, 1940, which is also a division of said patent.

The water-flow transmitter shown comprises a code wheel 15 having peripheral teeth corresponding to an alarm code on one half of the wheel 25 and a restoration code on the other half. The code wheel 15 is mounted upon a main shaft adapted to be actuated by the armature 16 of electromagnets 17 and 18, the main shaft also carrying cams 19 and 20. The transmitter 30 further comprises a second shaft geared to said main shaft and carrying the cams 21 and 22, said geared shaft being arranged, for instance, to make one revolution for every two revolutions of the main shaft. Since water-flow signals are sent during one and one-half revolutions of the code wheel and a restoration signal during one-half revolution of the code wheel, the cam 21 operates the master switch at 270° and 360° from normal, as shown.

The transmitter shown for the purpose of illustrating the invention is driven by current impulses from the central station. The impulses transmitted are converted by the code wheel into strong and weak impulses, respectively, weak impulses representing spaces in the code. The code impulses are arranged to operate a printer 25 at the central office, or any suitable code responsive mechanism connected to the marginal coding relay 26 which is operated by the strong code impulses.

The operation of the transmitter to send an alarm signal is initiated by the operation of the water-flow switch to the position in which the contacts 27 are closed. In the present instance, it is assumed that the closure of these contacts is

effected by means which is responsive to the flow of water in a sprinkler system. Obviously, the contacts arranged to initiate the operation of the transmitter may be closed manually or automatically in response to any condition which it is desired to indicate or record at a remote station. Likewise, the transmitter shown may also be initiated in operation by the closure of the contacts 28 of the tamper switch, these contacts being biased, for example, by a spring 29 to close when the cover of the water-flow switch is removed, or in response to tampering of the switch in any other desired manner. The operation of the tamper switch contacts 28 initiates the operation of the code transmitter, but in this instance a different code is transmitted, the code wheel 15 being employed for both the alarm and tampered codes. When both of the switches 27 and 28 have been restored from their operated position to normal, the code transmitter is again operated to send restoration codes in a manner that will be hereinafter described.

In the event that the flow detector operates the water-flow switch, the water-flow alarm code is transmitted as follows: Upon the closure of the contacts 27, a circuit is closed from positive battery through the contact 30 of relay 31, the ST conductor, the alarm contact 32 of the transfer cam 20, the contacts 27, the heating coil 35 of the thermostat 36, and the common conductor C to negative battery at the central station. The thermostat 36 starts to heat up but is not operated unless the water-flow contacts remain closed. In this manner the operation of the transmitter is prevented in case of a momentary closure of the contacts 27 owing to water hammer in the piping system, thus eliminating false alarms that would be caused by surges in the water pipes. In case the water flow maintains the contacts 27 closed, the thermostat bar 36 finally closes a circuit through contact 40 and connects the positive battery on the starting line through said contact and contact 41 of the master switch to the right hand magnet coil 18, which is also connected to negative battery on the common line C. The thermostat bar 36 is also arranged to latch the contacts controlled by the cam 22 in the normal position, as shown. The magnet 18 becomes energized and attracts its armature 16, thereby retracting the operating pawl into engagement with the next tooth on the main shaft and closing a circuit from the tap on the magnet coil 18 through the armature 16 and contact 42, contacts 43 of the master switch, the running conductor R and the outer windings of relay 45 to positive battery. The relay 45 is provided with two windings in series with the outgoing line R and a third winding in series with the in running line R as shown. This relay is provided for the purpose of supervising the running line conductors, being normally deenergized by the opposed windings connected in series with the ends of the running line loop, as explained more fully in my above-mentioned Patent No. 2,309,660. However, when the contacts 42 of the motor magnet of the transmitter connect negative battery to the left hand and right hand windings of the relay 45 in series with the low-resistance portion of the winding of the magnet 18, as described above, relay 45 becomes effectively energized and attracts its armatures. The closure of the armatures of relay 45 connects battery to the impulse starting conductor 47 to initiate the operation of the pulsing relays 48.

The pulsing relays 48 include separate contacts 49, 50 which are closed in properly timed relation

to control the energization of relay 31 which operates before the pulsing by contact 50 starts, and to transmit impulses through the winding of the coding relay 26, contact 51 of relay 31, contact 52 of relay 45, the left hand winding of relay 45 to the running conductor R of the loop circuit. When the motor magnet 18 becomes deenergized due to operation of relay 31, the main shaft of the transmitter is stepped one step and the cam 21 operates the master switch so that the running circuit is transferred through the contact 54 of the master switch to the winding of the motor magnet 18. It will be understood that the motor magnet 17 is connected in a similar way to the opposite running conductor of the loop to provide McCullough operation. At the end of three alarm codes transmitted by one and one-half revolutions of the main shaft, the transfer cam 21 opens the circuit through the contact 54 of the master switch to stop the transmitter. During the rotation of the code wheel 15, each tooth is effective to close contacts 55 to short-circuit the upper or high resistance portions of the windings of the motor magnets 17 and 18 so that the current flowing in the running circuit is increased. The strong current impulses traversing the coil of the marginal coding relay 26 close the contacts thereof and operate the associated printer or code-responsive mechanism 25.

39 The code wheel 15 is provided with teeth on one half of its periphery corresponding to the alarm code, as stated above, and on the other half with the restoration code. It may be assumed, for example, that the first digit of the alarm code consists of three teeth followed by two spaces, as shown in Fig. 2, and the restoration code consists of the similar grouping of teeth except that the second tooth of the first digit is missing, as shown in Fig. 3. Since the code wheel 15 rotates one and one-half revolutions to send three water-flow alarm signals, the second line impulse of the second code is normally of low current intensity, as in the restoration code. Since this code immediately follows one alarm code group, it will be recognized by its time of occurrence as a water-flow alarm signal. If desired, means such as that described in my parent application may be provided at the central station for converting the code into an alarm code so that the printer 25 will print three water-flow alarm signals before the transmitter stops.

After one and one-half revolutions of the main shaft for sending the three alarm codes as described, the transfer cam 20 is in a position displaced 180° from that shown in Fig. 1. Accordingly, a circuit will be closed through the restoration contact 57 associated with the transfer cam 20 for restarting the transmitter when the water-flow switch is restored and connects the starting conductor through contact 57, the normally closed contacts of the water-flow switch and tamper switch and the contact 41 of the master switch to magnet 18. The transmitter operates as described above for one-half a revolution of the main shaft. In this manner the restoration code is transmitted when the water-flow switch returns to normal, the transmitter being stopped by the opening of the contact 54 of the master switch after one restoration code has been transmitted.

70 The contacts 28 of the tamper switch are arranged to be closed, for example, by the spring 29, when the cover of the water-flow switch is removed as described above, or in response to any other predetermined tampering with the switch. When the contacts 28 are

closed in this manner, the starting circuit of the transmitter is connected through contact 32 associated with the transfer cam 20, the contacts 28 of the tamper switch and the contact 41 of the master switch to start the transmitter in the same manner as described above in connection with the operation of the water-flow switch. In this case, however, the contacts 59 associated with the cam 22 are not locked open by the thermostat bar or latch 36 and thus are closed as soon as the transmitter is started. The closure of the contacts 59 connects the contacts 32 associated with the cam 19 in circuit with the high resistance windings of the motor magnets 17 and 18. Accordingly, when the contacts 32 are closed by the cam 19, an additional strong current impulse is added to the code represented by the teeth of the code wheels 15. Thus, as shown in Fig. 4, the tamper code alarm signal may be similar to the water-flow alarm signal of Fig. 2 except that the first digit consists of four impulses instead of three, by proper location of the lobes of the cam 19. Likewise, when the tamper switch is restored to normal, opening the contacts 28, the tamper restoration code is transmitted, which may be a code similar to the water-flow restoration code shown in Fig. 3 except that the fourth impulse is a strong current impulse instead of a weak current impulse. In this manner different codes are transmitted by the transmitter for water-flow alarm and for tamper signals by employing the cam 19 under the control of the contacts 59 to add one or more supplemental impulses to those normally transmitted by the teeth in the code wheel 15.

The alarm signal transmitted and also the restoration signal transmitted depends for its character on which of the switches 27 or 28 is first operated. For example, if switch 27 is moved to alarm position and maintained in that position long enough for the thermostat bar 36 to complete its latch action closing contact 40, a water-flow alarm signal will be transmitted and even though the switch 28 be subsequently moved to alarm position, such movement will not result in the transmission of a tamper alarm signal due to the fact that the alarm initiating circuit closed by the contacts 32 is open once the transmitter operation has begun (by action of relay 31 in breaking contact 30). Should both switches 27 and 28 operate in almost simultaneous fashion, the signal transmitted will depend entirely on whether the contact 40 has been closed and the mechanical latch afforded by bar 36 has been completed. If such latching of the contacts to maintain contact 40 closed has not been accomplished, then the signal transmitted will be a tamper alarm signal. Likewise, once an alarm signal of either character has been transmitted, the restoration signal which will be transmitted in the second part of the divided cycle of transmission will be the restoration signal corresponding to the alarm signal. For example, should the alarm signal be initiated by the switch 27, and should the switch 28 be subsequently operated to alarm position as before stated the alarm signal will be a water-flow alarm. But should the switch 27 be moved to restoration position followed by restoration of switch 28, still the restoration signal will be for the water-flow indication since contact 40 has been maintained in locked position until the lobe of cam 22 is restored to its starting position relieving the pressure on bar 36 sufficiently to permit unlatching of contacts 40. Likewise

should the alarm have been initiated by switch 28 and the alarm signal for that condition transmitted, even though switch 27 is subsequently operated and then returned to normal prior to restoration of switch 28, the restoration signal will be that associated with switch 28 since under these conditions it would have been impossible to close switch 40 and maintain the latch in closed position. It is evident, of course, that both switches 27 and 28 must be in normal position before the proper restoration signal can be transmitted. From the foregoing it will be seen that transmission occurs in two parts of a divided cycle and the system is so constructed that conditions established at the initiation of transmission are maintained for both parts of the cycle or, in other words, for a full cycle of transmission, with the result that the character of signals cannot be varied to indicate different conditions during a full cycle of transmission.

Various modifications in the transmitter shown and described for the purpose of explaining the invention will occur to those skilled in the art and may be made without departing from the scope of the invention as defined in the appended claims.

I claim:

1. In combination, a code wheel current-impulse transmitting means for transmitting different signals during each division of a divided cycle of operation, the signals transmitted in the divisions of said cycle of operation being indicative of different conditions of the control means of said transmitting means, control means for initiating operation of said transmitting means, second control means for initiating operation of said transmitting means and for modifying said signals to cause the operation of the transmitting means to transmit different signals, and means for preventing modification of the character of signals being transmitted during a complete cycle of operation of said transmitting means.

2. In combination, transmitting means including a code wheel having a series of teeth to transmit a predetermined different code during each division of a divided cycle of operation, the signals transmitted in the divisions of said cycle of operation being indicative of different conditions of the control means for said transmitting means, control means for initiating operation of said transmitting means, second control means for initiating operation of said transmitting means and for modifying the code transmitted thereby, and means for rendering either of said control means inoperative to initiate operation of said transmitting means prior to the completion of a full cycle of operation thereof initiated by the other control means.

3. A transmitter comprising a main code transmitting means adapted to transmit predetermined different signals during each division of a divided cycle of transmission, said divisions of a divided cycle being indicative of different conditions of the transmitting means control means, a supplementary code transmitting means operatively associated with the first-mentioned transmitting means, control means for rendering said first-mentioned transmitting means operative independently of the supplementary code transmitting means to transmit signals, control means for rendering both of said code transmitting means operative at the same time to create modified different signals during each of said divisions of said divided cycle of

transmitting means operation, and means positively maintaining a selected transmitting condition during a complete cycle of transmitting means operation.

4. A transmitter comprising a main code transmitting means adapted for transmitting predetermined different signals during each division of a divided cycle of transmitting means operation, said divisions of a divided cycle being indicative of different conditions of the transmitter initiating means, a supplementary code transmitting means for altering said signals to create different signals during each division of said divided cycle, an initiating means for operating the main code means, a second initiating means to render the main code and supplementary means operative to transmit altered different signals during each division of said divided cycle, and means for rendering either of said initiating means inoperative to initiate operation of the transmitting means prior to the completion of a full cycle of transmitting means operation initiated by the other of said initiating means.

5. A transmitter comprising code transmitting means for transmitting predetermined main signals during each part of a divided cycle of transmitter operation, means for modifying the signals transmitted during each part of a divided cycle of transmitter operation, the signals transmitted in the parts of a divided cycle of transmitter operation being indicative of different conditions of the control means for said transmitting means and main and second control means movable selectively to initiate operation of the transmitting means to transmit main and modified signals respectively during the first part of said divided cycle, each of said control means being operable when restored to normal position to cause operation of said transmitting means to complete the signalling cycle thereof, said control means being so related that transmission of signals initiated by one thereof prevents initiation of signal transmission by the other thereof prior to the completion of the initiated full cycle of signal transmission.

6. A transmitter comprising code transmitting means for transmitting predetermined main signals during each part of a divided cycle of transmitter operation, means for modifying the signals transmitted during each part of a divided cycle of transmitter operation, the signals transmitted in the parts of a divided cycle of transmitter operation being indicative of different conditions of the control means for said transmitting means and main and second control means movable selectively to initiate operation of the transmitting means to transmit main and modified signals respectively during the first part of said divided cycle, each of said control means being operable when restored to normal position to cause operation of said transmitting means to complete the signalling cycle thereof, said control means being so related that transmission of signals initiated by one thereof prevents initiation of signal transmission by the other thereof prior to the completion of the initiated full cycle of signal transmission, said control means being so related that the second part of a cycle of signalling can be initiated only when both of said control means are in their normal positions.

7. A transmitter comprising a main code means for transmitting signals, a second code means adapted to add to said signals, main signal initiating means, a second signal initiating means for starting the main code means, a device set in

operation by the main signal initiating means for operating the main code means, and means to render said second code means operative when the device means is not operated.

5 8. A transmitter comprising a pair of lines, a motor, main and second code transmitting means operated by the motor, the main code means adapted for predetermined signals, the second code means adapted to add to said signals to form 10 second predetermined signals, a heater connected to one line, a normally open starting switch connected between the other line and the heater, a thermostat switch element adapted when flexed by the heater to connect said motor between the lines and means controlled by the thermostat to render said second code means capable of operation.

9. A transmitter for transmitting signals differing from one another in their characteristics 20 comprising a motor, a code transmitting switch driven thereby and including a wheel having alternate sets of teeth, and contacts operated thereby for transmitting first signals followed by second signals, an operating circuit for energizing the motor including a line, a main control switch having a normally closed contact and a normally open contact, a secondary control switch having a normally closed contact and a normally open contact, means associated with 25 said secondary control switch for modifying said first and second signals, a cam operated transfer switch driven by the motor connected to the line for successively establishing connections from the line to the normally open contacts and the normally closed contacts, a thermostatic auxiliary switch connected to the normally open contact of the main control switch adapted to close its contacts after a certain period of current flow, a cam operated master switch driven by the motor and having certain normally closed contacts 30 connected to the main control switch and the secondary control switch for completing a starting connection to the motor when the normally open contact of one of the control switches is 35 closed while the other thereof is in normal position, and other contacts operated by the cam for connecting the code contacts to a transmission line for code transmission until the code wheel has completed an odd number of half revolutions to thereby transmit a first signal and for subsequently connecting the code contacts to the transmission line until the code wheel has completed another half revolution to transmit a second signal in response to the restoration of the 40 abnormal control switch to normal position.

10. A transmitter for transmitting signals differing from one another in their characteristics comprising a motor, a code transmitting switch driven thereby and including a wheel having alternate sets of teeth and contacts operated thereby for transmitting first signals followed by second signals, an operating circuit including a line, a main control switch having normal and abnormal positions, a secondary control switch having normal and abnormal positions, means associated with said secondary control switch for modifying said first and second signals, a cam operated transfer switch driven by the motor and connected to the line for successively preparing 45 circuits which can be completed by the control switches for initiating transmission of first or second signals, a thermostatic auxiliary switch connected to the abnormal position of the main switch and adapted to delay the effect of operation 50 of this switch whereby false signals are pre- 55

vented, and a motor driven master switch for completing a starting connection to the motor when one of the control switches is moved to abnormal position while the other is in normal position and for connecting the code contacts to a transmission line to thereby transmit a first signal of character determined by the abnormal control switch and for subsequently connecting the code contacts to the transmission line to transmit a second signal in response to actuation of the abnormal switch to normal position.

11. A transmitter for transmitting signals differing from one another in their characteristics comprising a motor, a code transmitting switch driven thereby and including a wheel having alternate sets of teeth and contacts operated thereby for transmitting first signals followed by second signals, an operating circuit including a line, a first switch having a normally closed contact and a normally open contact, a second control switch having a normally closed contact and a normally open contact, means associated with said second control switch for modifying said first and second signals, a cam operated transfer switch driven by the motor and connected to the line for successively establishing connections from the line to the normally open contacts and the normally closed contacts, and a cam operated master switch driven by the motor and having certain normally closed contacts connected to the first control switch and the second control switch for completing a starting connection to the motor when the normally open contact of one of the control switches is closed while the other thereof is in normal position, and other contacts operated by the cam for connecting the code contacts to a transmission line for code transmission until the code wheel has completed an odd number of half revolutions to thereby transmit a first signal of character determined by the abnormal control switch and for subsequently connecting the code contacts to the transmission line until the code wheel has completed another half revolution to transmit a restoration signal in response to actuation of the abnormal control switch to normal position with the other control switch also in normal position.

12. A transmitter for transmitting signals differing from one another in their characteristics comprising a motor, a code transmitting switch driven by the motor for transmitting first signals followed by second signals, an operating circuit including a line, a main control switch having an abnormal position and a normal position, a secondary control switch having an abnormal position and a normal position, means associated with said secondary control switch for modifying said first and second signals a motor-operated

transfer switch connected to the line for successively establishing connections from the line to the abnormal positions and normal positions of the main control and secondary control switches, and a master switch for completing a starting connection to the motor and for connecting the code switch to a transmission line for code transmission when one of said control switches is moved to abnormal position while the other control switch is in normal position.

13. A transmitter of the character described comprising a motor, code transmitting means driven thereby and including a unidirectional code wheel and contacts operated thereby for transmitting signals, a plurality of sets of signal initiating contacts, means associated with one set of contacts for modifying the signals transmitted by said transmitting means a transfer switch means for successively establishing connections to the contacts of said sets and means for completing a starting connection to the motor upon the operation of any of said sets of initiating contacts while the other of said sets of initiating contacts are in normal position.

14. A transmitter for transmitting different code groups comprising a motor, a code transmitting means including a unidirectional code wheel driven by the motor, an operating circuit including a line, a plurality of control switches having abnormal and normal positions, means associated with one of said control switches for modifying the signals transmitted by said transmitting means, a motor operated transfer switch connected to the line for successively establishing connections from the line to the abnormal and normal positions of said switches and a master switch for completing a starting connection to the motor and connecting the code transmitting switch to the line for code transmission.

15. A transmitter for transmitting different signal code groups comprising a motor, control means therefor, a code transmitting switch including a code wheel driven by the motor for transmitting first signals followed by second signals during the parts of a divided cycle of transmission, the signals transmitted in the parts of said divided cycle being indicative of different conditions of the control means for said transmitter a master switch operated by said motor for completing a starting connection to the motor and connecting the code switch to a transmission line for code transmission, contacts operated by the motor for interpolating code impulses in the signal code transmitted, and means for maintaining said contacts in operation during a complete cycle of signal transmission.

MANFRED W. MUEHTER.
